UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

DOUBLE-SEAMING MACHINE.

No. 866,102.

Specification of Letters Patent.

Patented Sept. 17, 1907.

Application filed November 8, 1905, Serial No. 286,346.

To all whom it may concern:

Be it known that I, GEORGE W. WEBER, a citizen of the United States, residing in New York, in the county of New York and State of New York, have invented a new and useful Improvement in Double-Seaming Machines, of which the following is a specification.

My invention relates to improvements in double seaming machines.

10 Heretofore in double seaming the covers on sheet metal cans, difficulty has been experienced in producing with reliability, regularity and uniformity, perfect and liquid or hermetically tight seams on the cans, owing to the fact that frequently the seaming flange on the can body is more or less irregular or uneven, or has become more or less battered, dented or misshaped in handling or shipment of the cans. And the object of my invention is to provide a machine or mechanism by which this objection or difficulty in the production

20 of perfect and tight seams may be overcome or avoided. My invention consists in the means I employ to practically accomplish this object or result. That is to say, it consists in connection with the can clamping chucks by which the can body and head are clamped and held 25 during the seaming operation, and suitable seaming rollers, of a flange straightening roller operating in advance of the seaming rollers to straighten the seaming flange on the can body preparatory to the seaming operation.

30 My invention also consists in the novel construction of parts and devices, and in the novel combinations of parts and devices herein shown and described.

In the accompanying drawing forming a part of this specification, Figure 1 is a side elevation of a double seaming machine embodying my invention. Fig. 2 is a horizontal section on line 2—2 of Fig. 1. Fig. 3 is a vertical section on line 3—3 of Fig. 2 and showing the flange straightening roller in operation, and Figs. 4 and 5 are detail sections illustrating the operation of

40 the seaming rollers.

In the drawing, A represents the frame of the machine; B is the lower chuck and C the upper chuck for clamping and holding the can body X and can head or cover X¹ during the flange straightening and seaming operations. The lower can chuck B upon which the can rests, reciprocates vertically to clamp the can and cover against the upper chuck C. D represents the seaming head, the same being furnished with a pair of seaming rollers d d¹ for folding together the 45 seaming flanges x on the can body and x¹ on the can head or cover and forming the double seam. All these parts may be of any ordinary or suitable construction now commonly in use and familiar to those skilled in the art. In the drawing, I have for convenience illus-

55 trated the can chucks B C as rotary ones for rotating the cans in respect to the seaming head, but if desired, the can chucks may be non rotary and the can thus held stationary while the seaming head and seaming rollers are revolved about its axis in a manner well known to those skilled in the art.

60 The seaming head D in addition to the necessary seaming rollers d d¹ carried thereby, is preferably furnished with a flange supporting roller d² which cooperates with the flange straightening roller f to support the can body flange x and cover X¹ against the upward thrust of the flange straightening roller f, which operates to straighten the flange of the can body preparatory to the seaming operation.

65 The flange straightening roller f is preferably journaled upon a slide F by a pin or stud f¹; and this slide F is reciprocated in its guides F¹ as required, preferably by means of a lever F², connecting pin F³ and cam F⁴, which latter is preferably secured to the seaming head D by a bolt F⁵ so that when the seaming head D is operated to bring the flange supporting roller d² into 70 position, the flange straightening roller f will be automatically operated by the movement of the seaming head. The operating slide F for the flange straightening roller f is retracted and normally held in its retracted position by the spring f². The slide operating 75 lever F² and the connecting pin F³ are carried upon the main bracket G¹ which carries the seaming head bracket G. The main bracket G¹ and with it the seaming head bracket G may be adjusted up and down as required by the adjusting screw g and is fixed in position on the frame A by a bolt g¹. The bracket G carries a pivot or stud g² upon which the seaming head D turns or rocks.

80 The lower can chuck B may be reciprocated as required by any suitable means, the mechanism for this purpose represented in the drawing being a treadle H, link h, and lever h¹ which connects with the stem B¹ upon which the chuck B is journaled by a pin or stud b. The upper chuck C has a shaft C¹ journaled in the frame of the machine and carrying a pulley C² by 85 which the upper chuck and the can are rotated by a belt C³ from the pulley C⁴ on the driving shaft C⁵. The seaming head D carrying the seaming rollers and the flange supporting roller may be operated by any suitable means, that illustrated in the drawing being a 90 handle or lever D¹. I prefer to mount the flange supporting roller d² on the seaming head, as it thus may be operated or moved into operative position by the same means employed for actuating the seaming rollers.

100 While in the drawing I have illustrated my flange straightening invention or improvement as applied to one well known form or kind of double seaming machine, I desire it to be understood that it is equally

adapted for use with other kinds of seaming machines now commonly in use or familiar to those skilled in the art.

The seaming head carrying bracket G is mounted on 5 a bracket G¹ and may be adjusted to and from the axis of the can chuck by means of an adjusting screw g⁴ and clamp nut g³.

I claim:

1. In a double seaming machine, the combination with 10 a pair of chucks for clamping the can body and can head or cover, of seaming rollers and a flange straightening roller operating in advance of the seaming rollers to straighten the seaming flange on the can body preparatory to the seaming operation, substantially as specified.
- 15 2. The combination with a pair of chucks for clamping and holding the can, of seaming rollers, and means for straightening the seaming flange on the can body preparatory to the seaming operation, substantially as specified.
- 20 3. The combination with a pair of can chucks, of seaming rollers and a flange straightening device for straightening the horizontal flange on the can body preparatory to the seaming operation, substantially as specified.
- 25 4. The combination with a pair of can chucks, of a flange supporting roller and a flange straightening roller for straightening the horizontal flange on the can body preparatory to the seaming operation, substantially as specified.
- 30 5. The combination with a pair of can chucks, of a seaming head, a flange supporting roller mounted thereon, and a flange straightening roller for straightening the horizontal flange on the can body preparatory to the seaming operation, substantially as specified.
- 35 6. The combination with a pair of can chucks, of a seaming head, a flange supporting roller mounted thereon, a flange straightening roller and means for operating the flange straightening roller from the seaming head, substantially as specified.
- 40 7. The combination with a pair of chucks for holding and rotating the can, of a flange supporting roller, a movable head upon which it is mounted, a flange straightening roller and means for operating the flange straightening roller from the movable head carrying the flange supporting roller, substantially as specified.
- 45 8. The combination with a pair of chucks, of a seaming head, a flange supporting roller mounted thereon, a cam carried by said head, a flange straightening roller, a slide upon which said flange straightening roller is mounted and a connecting lever and pin for operating the flange straightening roller from said head carrying the flange supporting roller, substantially as specified.
- 50 9. The combination with chucks for clamping the can and cover, of a seaming head, seaming rollers carried thereby, a flange supporting roller carried by said seaming head and a flange straightening roller operated by the movement of the seaming head, substantially as specified.
- 55 10. The combination with chucks for clamping the can and cover, of a seaming head, seaming rollers carried thereby, a flange supporting roller carried by said seaming head and a flange straightening roller, a movable slide upon which the flange straightening roller is journaled and connecting means for operating said slide from and by the seaming head, substantially as specified.

11. In a double seaming machine for cans a supplementary straightening roller and means for moving said roller upwardly and forwardly to engage with the under surface of the body flange, immediately, before the engagement of the seaming rollers with the flanges. 65

12. In a double seaming machine for cans, a supplementary, straightening roller and means for moving said roller into engagement with the lower surface of the body flange, to straighten said flange, against the cap flange. 70

13. In a double seaming machine for cans, the combination with a suitable frame and a horizontally operating seaming tool, of a supplementary straightening roller 75 suitably supported and means for moving said roller momentarily into engagement with the body flange, before the engagement of the seaming tool therewith.

14. In a double seaming machine for cans the combination with a suitable frame, of a seaming tool journaled on 80 the frame, and adapted to be swung in a path parallel with the cap and body flanges into engagement therewith, a supplementary straightening roller and means to move said roller upwardly into engagement with the under surface of the body flange to straighten said body flange immediately before the engagement of the seaming tool with said flanges. 85

15. In a double seaming machine for cans, the combination with a suitable frame, a support for the cans, means to rotate the can support and the can while the can is 90 being seamed, a seaming tool journaled on the frame and seaming rollers on said tool, of a supplementary straightening roller supported on the frame, and means operated by the seaming tool for moving said supplementary roller upwardly into engagement with the lower surface of the 95 body flanges, immediately before the seaming rollers engage with the cap and body flanges.

16. In a double seaming machine for cans, the combination with a suitable frame, of a seaming tool journaled on the frame and provided with a plurality of seaming 100 rollers, said tool being adapted to be swung in a horizontal plane to bring its rollers into engagement with the cap and body flanges, a supplementary straightening roller and means to move said roller upwardly into engagement with the under surface of the body flange immediately before the 105 engagement of the seaming tool with the flanges.

17. In a double seaming machine for cans, the combination with a suitable frame, of a seaming tool journaled on the frame and adapted to be swung into engagement with the cap and body flanges to form the seam, a supplementary straightening roller and means to move said roller upwardly to bring its periphery into engagement with the under surface of the body flange, immediately before the engagement of the seaming tool with said flanges. 110

18. In a double seaming machine for cans, a supplementary straightening roller and means for moving said roller upwardly to bring its periphery into engagement with the under surface of the body flange to straighten said body flange, immediately before the engagement of the seaming rollers with said flange. 115
